MECHANISM FOR RECLAIMING TOBACCO FROM REJECTED FILTER TIP CIGARETTES

Daniel Adolph Di Ianni, Toronto, Ontario, Canada, assignor to American Machine & Foundry Company, a corporation of New Jersey

Filed Oct. 6, 1960, Ser. No. 60,894

3 Claims. (Cl. 131—96)

This mechanism relates to an apparatus and method for reclaiming tobacco from rejected cigarettes, and particularly filter tip cigarettes.

Various devices and methods have been devised for salvaging tobacco from rejected cigarettes. Some have broken the rejected cigarettes so as to separate the tobacco and paper wrappers and then the broken material is winnowed or sent through a sifting screen where the paper and mouthpiece material is separated from the tobacco. This has not been entirely satisfactory because it has broken the tobacco up into undesirable smaller pieces, and the separation of the paper and the tobacco has not been as readily attained as is desired.

It is an object of this invention to provide a tobacco reclaiming apparatus for rejected cigarettes, which will be of simple design and will be reliable in operation.

Another object of this invention is to provide a simple method for reclaiming tobacco in defective cigarettes.

Another object of this invention is to provide a tobacco reclaiming apparatus which will salvage tobacco from the rejected cigarettes by blowing the tobacco out of the defective cigarette.

Another object of this invention is to provide a reclaiming apparatus wherein pins are provided for holding the cigarette mouthpiece while air blows the tobacco out from the cigarette wrapper.

A further object of this invention is to provide a tobacco reclaiming apparatus for defective cigarettes wherein cigarettes are fed to a conveyor which holds and moves the cigarette past an air station where air blows the tobacco out from the cigarette wrapper.

Another object of this invention is to provide a salvaging mechanism wherein the wrapper of the cigarette is weakened for at least part of its length and wherein air is employed to blow out tobacco from the gripped cigarette.

Other objects and features of the invention will appear as the description of the particular embodiment selected to illustrate the invention progresses. In the accompanying drawings, which form a part of this specification, like characters of reference have been applied to corresponding parts throughout the several views which make up the drawings.

FIG. 1 is an end elevation showing the tobacco reclaiming apparatus.

FIG. 2 is a cross sectional side elevation taken on the line 2—2 of FIG. 1.

FIG. 3 is an enlarged elevational view of the defective cigarette conveying drum, and the perforating mechanism, and a portion of the feed hopper for defective cigarettes.

FIG. 4 is a partial sectional plan view taken on the line 4—4 of FIG. 3.

FIG. 5 is an enlarged sectional view taken on the line 5—5 of FIG. 4.

FIG. 6 is a detailed view showing the perforating mechanism.

FIGS. 7, 8, 9, and 10 show various orifice configurations for blowing air through the length of cigarettes.

Defective cigarettes are placed in the hopper 10. Suitable mechanism is provided for vibrating the bottom floor 12, the sliding floor 14, and the baffles 16. Suitable deflectors 18 and 20 are employed for lining the defective

2

cigarettes up side by side as well as for supporting some of the weight of the cigarettes that would normally be exerted on the lowermost defective cigarettes. A suitable curved cigarette supporting pocket 22 is provided at the bottom of the hopper 10 for directing the cigarettes to the pick-up conveyor.

It will be evident from the foregoing description that the vibratory mechanism will cause cigarettes to advance over the deflectors 18 and 20 and 16, along the vibratory floors 12 and 14. By positioning the floors 12 and 14 relatively close to each other and the deflector plate 16 above the same, it has been found that this prevents a jam from occurring at this point and the defective cigarettes are fed systematically into the range of the pockets of conveyor 24.

As the conveyor 24 rotates in the direction indicated by the arrow, cigarettes are picked up by the pockets 26. The cigarettes are pushed back against the rear face or back flange 25 of the drum by plow 78 so that air may be passed from one end of the cigarettes clear through to the other end by means of orifices 41. As the cigarettes pass by the slitting drum 28, slitting or piercing members 30 penetrate the side of the defective cigarettes, thereby weakening the wrapper along its length. It will be appreciated that while I have shown and described a slitting device, this may, if desirable, be omitted, depending on the type of tobacco and wrapper that is employed. In some instances my invention will work equally as well without any pre-weakening of the wrapper.

When the cigarettes, slit in this manner, come into the range of action of drum 32, the pins 34 carried by the drum 32 engage the end of the cigarette (FIGS. 1 and 4). When the cigarette so gripped in this manner reaches a point 35 which is approximately in line with the shaft 36 of the drum 24 and the shaft 38 of the drum 32, it will be opposite to the blower 40, which is connected to a suitable supply of compressed air by means of a hose 42.

Referring to FIGURE 2, the tensioning spring 48 pulls the shaft 36 and drum assembly 24 against the blower nozzle so that good sealing may be effected. The shaft 36 is supported by brackets 52 and 54.

A ratchet clutch mechanism 56 connected to the main drive sprocket 58, drives shaft 36.

A cam roller 60 is attached to the reciprocating fork 62 which drives the above described vibratory baffles 16 in the hopper. The cam roller 60 tracks on cam 64. A ratchet mechanism 66 drives the lower agitators 12 and 14 by means of fork 72, as shown in FIG. 1.

A spur gear 68 is coupled through a train of gears to a spur gear 70 which is attached to the refuser roller 74. The fork 72 is actuated by ratchet mechanism 66 and is coupled to the vibrator floor 12 shown in FIGURE 1.

A refuser roller 74 allows only the required amount of defective cigarettes to pass to the pockets 26 of the drum assembly 24. A plow 78 forces the cigarettes back against the rear face 25 of the drum.

In FIGURE 5, I have shown how the compressed air from the pneumatic hose 42 is automatically valved by the surface of drum 24, so as to avoid having a loss of compressed air at this point, except during the actual elimination of tobacco from the gripped cigarette. At this time orifices 41 formed in drum 24, pass by the air jet 40.

Because the cigarette has been weakened along its length by the slitting or perforating members 30, when air is injected through the end of the cigarette, the cigarette wrapper will not burst but will instead open at the slit—thereby enabling the wrapper 39 and mouthpiece portion 37 to be held by pins 34 of drum 32 while tobacco is blown from the defective cigarette.

When the tobacco has been eliminated from the cigarette in this manner, the drum 32, rotating in the direction indicated by the arrow, brings the defective cigarette paper and filter held by pins 34 of drum 32 into the range of action of the stripper 44, which removes the paper and mouthpiece. A suitable duct 46 is positioned immediately in front of position 35 to receive the tobacco blown out from the cigarette by the compressed air coming out of the orifice 41 through the compressed air hose 42.

To facilitate ejecting the tobacco, it has been found that certain orifice openings sometimes tend to be more effective with certain types of tobacco and mouthpieces than other shaped orifice openings. For example, I have shown in FIG. 7, FIG. 8, FIG. 9, and FIG. 10, four different types of openings which could be employed for this purpose in the conveyor 24.

A single round orifice opening, however, could also be employed without the necessity of resorting to a particular shape or a particular design or orifice opening.

The invention hereinabove described may therefore be varied in construction within the scope of the claims, for the particular device selected to illustrate the invention is but one of many possible embodiments of the same. The invention, therefore, is not to be restricted to the precise details of the structure shown and described.

What is claimed is:

1. A device for reclaiming tobacco from defective cigarettes, comprising means for conveying cigarettes past a reclaiming station, a piercing device for weakening the cigarette wrapper in an axial direction along its length, means for gripping said cigarettes, and means for blowing air through the length of said cigarette having said wrapper weakened at said reclaiming station to remove substantially all tobacco from the length of the cigarette.

2. Apparatus for reclaiming tobacco from defective

cigarettes which comprises means for feeding defective cigarettes, a fluted conveyor drum for receiving said defective cigarettes, a pin for piercing the mouthpiece end of the defective cigarette to maintain the same free from axial movement while maintaining the air passageway through the mouthpiece unrestricted and means for blowing a stream of air axially into the mouthpiece end of the cigarette to eject substantially all the shredded tobacco from the cigarette.

3. Apparatus for reclaiming shredded cigarette tobacco from defective mouthpiece cigarettes comprising, a fluted drum, a feed for delivering mouthpiece cigarettes to the flutes of said drum with the mouthpiece ends all facing in the same direction, stops for positioning said mouthpiece cigarettes in said flutes, pins for piercing the mouthpiece ends of said cigarettes to maintain them free from axial movement, a blower for blowing air axially into the mouthpiece end of and through the length of each of said cigarettes and means for rotating said drum to bring said cigarettes successively in front of said blower to cause the shredded tobacco to be blown out from said wrapper by air blown through the mouthpiece ends of the cigarettes to remove substantially all of the tobacco from each cigarette.
